US00D673957S

(12) **United States Design Patent**
Lin et al.

(10) **Patent No.:** US D673,957 S
(45) **Date of Patent:** ** Jan. 8, 2013

(54) **NOTEBOOK COMPUTER CONNECTOR**

(75) Inventors: **Cheng-Jui Lin**, Taipei (TW); **Yi-Nung Lee**, Taipei (TW); **Yung-Hsiang Chen**, Taipei (TW)

(73) Assignee: **Compal Electronics, Inc.**, Taipei (TW)

(**) Term: **14 Years**

(21) Appl. No.: **29/404,068**

(22) Filed: **Oct. 14, 2011**

(51) LOC (9) Cl. **14-02**

(52) U.S. Cl. **D14/434**

(58) **Field of Classification Search** .... D14/432–434, D14/314, 204, 420, 421, 217, 315–327; D18/1, D18/2, 7, 11; 235/145 A, 145 R; 341/22, 341/23; 345/104, 156, 168, 169, 173, 87, 345/901–905; 361/679.01–679.27, 679.14, 361/679.31, 679.32, 679.4, 679.41, 679.43, 361/679.55; 400/486, 489; 710/14; D13/107, D13/108, 146; 248/346.03, 176.1; 320/109, 320/112–115

(57) **CLAIM**

The ornamental design for an notebook computer connector, as shown and described.

DESCRIPTION

FIG. 1 is a perspective view of an notebook computer connector showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the notebook computer connector of our design in use.

The broken lines shown represent unclaimed subject matter and form no part of the claimed design.
